UNITED STATES PATENT OFFICE

ROBERT C. OSGOOD, OF CLAREMONT, NEW HAMPSHIRE, ASSIGNOR TO SULLIVAN MACHINERY COMPANY, A CORPORATION OF MASSACHUSETTS

HOISTING MECHANISM

Application filed July 12, 1930. Serial No. 467,541.

This invention relates to hoisting mechanisms and more particularly to improvements in double drum hoists of the so-called "slusher" type especially adapted to use in drag scraper work. From another aspect it relates to improvements in hoists whereby plural speed traction is attainable.

In accordance with the so-called "slusher" system of handling ore and like materials a double drum hoist is usually employed for moving the drag scraper back and forth relative to the material to be loaded. Such hoists are of a comparatively high powered, compact character, and a pair of winding drums, as for instance a haulage drum, and a tail rope drum are usually provided driven from a common source of power. Drag lines or ropes are usually connected to these drums and cooperate with a drag scraper, the latter being movable back and forth relative to the loose material to be handled to convey the latter to a chute or car in a manner well understood in the art. Under certain conditions it has been found highly desirable to provide a multi-speed drive for the haulage drum to thereby obtain a slow speed movement of the drag scraper during its digging and loading functions and to attain a relatively high speed drive of the haulage drum for haulage purposes, it also being highly desirable to drive the tail rope drum at a similar high speed to drag the empty scraper back to its digging and loading position.

It is also desirable to be able, in hoists for other purposes, as well as for slushing, to effect rotation of a winding drum at different speeds, and with correspondingly different tractive capacities, to handle different loads or meet other varying conditions.

One object of the present invention is to provide improved plural speed driving means for a hoist drum. Another object is to provide improved plural speed, variably controllable driving mechanism for a drum permitting a wide range of control or complete interruption of drive when desired. A further object of this invention is to provide an improved hoisting mechanism of the double drum "slusher" type having improved multi-speed driving means for the haulage

drum so that the drag scraper may be operated to dig and load and to convey material in an improved manner. Another object is to provide an improved double drum hoist having an improved plural speed planetary driving means for the haulage drum and improved drive control means therefor. A further object is to provide an improved double drum hoist having improved driving and supporting means for the drums and an improved arrangement of the drums on the aforesaid supporting means and improved control means therefor so that the drums may be driven and controlled in an improved manner. These and other objects of this invention will, however, hereinafter more fully appear in the course of the ensuing description and as more particularly pointed out in the appended claims.

In the accompanying drawings there is shown for purposes of illustration one form which the invention may assume in practice.

In these drawings,—

Fig. 1 is a central longitudinal vertical sectional view through an illustrative embodiment of the improved hoisting mechanism.

Fig. 2 is a transverse vertical sectional view taken substantially on line 2—2 of Fig. 1.

Fig. 3 is a transverse vertical sectional view taken substantially on line 3—3 of Fig. 1, with the brake band operating means shown in applied position.

In this illustrative embodiment of the invention there is shown a double drum hoist generally designated 1 and having a frame or portable base 2 which has secured thereto upstanding end brackets or supports 3 and 4. As illustrated, detachably secured at one end to the frame 2 is a supplemental base frame 5 and this supplemental base frame forms a support for a motor 6 which may be of the uni-directional electric type although it is obvious that any other suitable type of motor may be utilized if desired. The motor 6 is detachably secured to the frame 5 and secured to the armature shaft 7 of this motor is a motor pinion 8 meshing with an internal gear 9 keyed to one end of a longitudinally extending horizontal driving or transmission shaft 10 herein arranged parallel with

the motor axis and journaled at its opposite ends in a manner hereinafter described within the upstanding supports 3 and 4. The gears 8 and 9 are contained in a suitable casing or housing 11 detachably secured to the end bracket 3 and this casing is suitably perforated at 12 to permit the armature shaft 7 to extend thereinto. The casing is preferably made of two parts to permit access to the interior thereof. As shown, journaled on the shaft 10 as by anti-friction bearings 13 is a haulage drum 14, while likewise journaled on this shaft as by anti-friction bearings 15 is a tail rope drum 16. In the present construction arranged at one end of the haulage drum 14 is a slow speed drive control means, generally designated 17, for this drum, while interposed between the adjacent ends of the drums 14, 16 is a fast speed drive control means 18 for the haulage drum. There is also provided a drive control means generally designated 19, similar to the drive control means 18, for the tail rope drum 16. Now referring to the improved drive and control means for the haulage drum 14 and more particularly to the slow speed drive for this drum, it will be noted that keyed to the shaft 10 is a spur pinion 20 constantly in mesh with a planetary drum driver gear 21 journaled on anti-friction bearings 22 carried by a stub shaft 23 supported by the drum 14 as clearly shown in Fig. 1. The gear 21 is constantly in mesh with an internal gear 24 herein formed integral with a rotatable reaction member 25. This reaction member 25 is provided with a hub portion 26 journaled in a roller bearing 27 carried by the end bracket 3. Arranged within this hub 26 are anti-friction bearings 28 in which the adjacent end of the shaft 10 is journaled. It will also be noted that the reaction member 25 is provided with a frictional braking surface 29 with which a suitable contractible brake band 30 cooperates. Now referring to the relatively high speed drive for the haulage drum 14 it will be observed that keyed to the shaft 10 intermediate its ends is a spur pinion 31 of greater diameter than the pinion 20 above referred to and constantly meshing with a planetary drum driver gear 32 journaled on anti-friction bearings supported by a stub shaft 33 carried by the drum 14. In the present construction the drum driver gears 21 and 32 and their respective supporting structures are arranged at diametrically opposite sides of the drum 14, thereby providing a balanced construction and the heavier gear 21 has a lighter stub shaft so that static and dynamic balance are secured. The drum driver gear 32 is in constant mesh with an internal gear 34 herein formed integral with a rotatable reaction member 35 journaled on anti-friction bearings similar to the bearings 28 for the member 25 but suitably supported by the shaft 10. This

reaction member 35 is provided with a frictional braking surface with which a brake band 36, similar to the brake band 30, cooperates. Operating means for the brake bands 30 and 36, as will hereinafter be described, are provided whereby these brake bands may be selectively tightened to hold one or the other of the reaction members 25, 35 stationary or loosened to permit free rotation of these reaction members. It will thus be seen that upon application of the brake band 30 the reaction member 25 is held against rotation, and upon driving of the pinion 20 by the motor 6 the gear 21 rolls around the internal gear 24 as a trackway and moves with it the winding drum 14 at a relatively slow speed appropriate for moving the drag scraper to effect its digging and loading functions. When the brake band 30 is released and the brake band 36 applied, the reaction member 25 freely rotates while the reaction member 35 is held stationary. The pinion 31 then drives the gear 32, thereby causing the latter to roll around the internal gear 34 as a trackway, moving with it the winding drum 14 at a relatively high speed appropriate for moving the loaded scraper at a haulage speed.

Now referring to the control means for the brake band 30, it will be noted that pivoted at 37 to one end of the brake band is a lever 38 in turn connected through a pivoted link 39 to the other end of the brake band. Pivoted at 40 to the outer end of this lever is a link 41 pivoted at 42 to a crank or arm 43 fixed to an operating shaft 44 having a suitable operating lever 45. The operating means for the brake band 36 includes a similar lever 46 and link 47, this lever being connected by a link 48 to a crank or arm 49 likewise secured to the shaft 44 and extending in a direction diametrically opposite with respect to the shaft from the crank 43. When the lever 45 is in the position shown in Fig. 2 the lever 38 is in its downward position, applying the brake band 30 while the lever 46 is in its upper released position. Upon swinging of the lever 45 from the position shown in Fig. 2 to the position shown in Fig. 3 the lever 38 is swung upwardly into its released position while the lever 46 is swung downwardly to apply the brake band 36. It will thus be seen that when one of the brake bands is applied the other is always released and that when the lever 45 is in its central or neutral position both of the brake bands are released, thereby permitting the drum 14 to remain idle during running of the motor.

The driving means for the tail rope drum 16 is herein exactly the same as the high speed driving means for the drum 14 and includes a pinion 50 meshing with a planetary drum driver gear 51 in turn in constant mesh with an internal gear fixed to a reaction member 52. This reaction member is provided with a con-

trol mechanism similar to the control mechanism for the high speed drive for the haulage drum 14 and similar bearing and supporting structure is provided for the reaction member and shaft 10. The drums 14 and 16 are provided with usual frictional brake surfaces 53 and 54 with which usual brake bands cooperate for braking the drums when the latter are disconnected from their drive.

In the use of the improved double drum hoist, the control means 17 for the haulage drum 14 is operated to effect movement of the drag scraper at a relatively slow speed to effect the digging and loading function of the drag scraper, while the drive control means 18 is operated to effect rotation of the haulage drum at a relatively high speed to effect movement of the loaded scraper to effect its hauling function, that is, to effect movement of the loaded scraper from its loading position to its position wherein the material is discharged into the chute or car. The drive control means 19 for the tail rope drum 16 is operated to effect rotation of this drum at a speed similar to the high speed drive for the drum 14 to move the empty drag scraper rapidly from its discharging position back to its digging and loading position. These and other uses and advantages of the improved hoisting mechanism will be clearly apparent to those skilled in the art.

As a result of this invention, it will be noted that improved driving and controlling mechanism for a hoist drum is provided, by means of which two predetermined speeds of rotation are possible, and also a wide range of fractional speeds based on each of the predetermined speeds. Moreover, while a common drive shaft is provided, separate drive trains arranged primarily at opposite ends of the drum and arranged so that good dynamic balance is secured are employed, and each is provided with a frictionally controlled reaction member permitting wide range of control.

As a further result of this invention it will be noted that an improved double drum hoist is provided especially adapted to use with the so-called "slusher" system of handling ore or like materials wherein there is provided improved driving means for the drums and improved and simplified controlling means therefor. It will further be noted that an improved double drum portable hoist is provided of a comparatively high powered, and compact character. It will further be noted that an improved plural speed drive is provided for the haulage drum of a double drum "slusher" hoist, thereby increasing its efficiency in drag scraper loading, it being possible to operate the scraper in an improved manner during digging and loading while at the same time providing means for rapidly moving the loaded scraper toward its discharging position.

While there is in this application specifi-

cally described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a hoisting mechanism, a pair of coaxial relatively rotatable winding drums, a motor, and driving connections between said motor and drums including means for effecting rotation of one of said drums at either a relatively high or a relatively low winding speed, said driving connections comprising gear trains individual to each drum.

2. In a hoisting mechanism, a motor, a pair of coaxial relatively rotatable winding drums, driving connections between said motor and one of said drums for driving the latter at a relatively high or a relatively low speed, and driving connections between said motor and said other drum for driving the latter at a relatively high speed.

3. In a hoisting mechanism, a motor, a pair of relatively rotatable winding drums, and driving connections between said motor and drums for driving one of the latter at a relatively high or a relatively low speed including a low speed planetary drive control means and a high speed planetary drive control means.

4. In a hoisting mechanism, a motor, a pair of relatively rotatable winding drums, and driving connections between said motor and drums for driving one of the latter at a relatively high or a relatively low speed including a low speed planetary drive control means and a high speed planetary drive control means, and a separate planetary drive control means for said other drum.

5. In a hoisting mechanism, a motor, a pair of relatively rotatable winding drums, and driving connections between said motor and drums for driving one of the latter at a relatively high or a relatively low speed including a low speed planetary drive control means and a high speed planetary drive control means, and a separate high speed planetary drive control means for said other drum.

6. In a hoisting mechanism, a motor, a pair of relatively rotatable winding drums, and driving connections between said motor and drums including planetary drive control means for each drum for effecting drum rotation at one speed and a separate and distinct planetary drive control means for one of said drums for effecting rotation thereof at a different speed.

7. In a hoisting mechanism, a motor, a pair of relatively rotatable winding drums, and driving connections between said motor and drums including planetary drive control means for each drum for effecting drum rota-

tion at a slow speed and a separate and distinct planetary drive control means for one of said drums for effecting rotation thereof at a fast speed.

5 8. In a hoisting mechanism, a motor, a pair of relatively rotatable winding drums, a shaft on which said drums are journaled, driving connections between said motor and said shaft, driving connections between said 10 shaft and said drums for effecting drum rotation at one speed, and a separate driving connection between said shaft and one of said drums for effecting rotation thereof at a different speed.

15 9. In a hoisting mechanism, a motor, a pair of relatively rotatable winding drums, a shaft on which said drums are journaled, driving connections between said shaft and one of said drums for effecting drum rotation 20 at a slow speed, and a separate driving connection between said shaft and one of said drums for effecting rotation thereof at a fast speed.

25 10. In a hoisting mechanism, a motor, a pair of relatively rotatable winding drums, a shaft on which said drums are journaled, driving connections between said motor and said shaft, a slow speed driving connection between said shaft and one of said drums, and separate fast speed driving connections between said shaft and both of said drums.

30 11. In a hoisting mechanism, a motor, a pair of relatively rotatable winding drums, a shaft on which said drums are journaled, driving connections between said motor and said shaft, driving connections between said shaft and said drums for effecting drum rotation at one speed including a separate drive control means for each drum, and driving connections between said shaft and one of said drums for effecting drum rotation at a different speed including drive control means 35 separate and distinct from aforesaid drive control means.

40 12. In a hoisting mechanism, a motor, a pair of relatively rotatable winding drums, a shaft on which said drums are journaled, driving connections between said motor and shaft, driving connections between said shaft and said drums for effecting drum rotation at one speed including separate frictional drive control means for each drum, and driving connections between said shaft and one of said drums for effecting drum rotation 45 at a different speed including a frictional driving control means separate and distinct from aforesaid drive control means.

50 13. In a hoisting mechanism, a motor, a pair of relatively rotatable winding drums, a shaft on which said drums are journaled, driving connections between said motor and said shaft, driving connections between said shaft and said drums for effecting drum rotation at one speed including a separate 55 planetary drive control means for each drum,

and driving connections between said shaft and one of said drums for effecting drum rotation at a different speed including a planetary drive control means separate and distinct from aforesaid planetary drive control 70 means.

14. In a hoisting mechanism, a motor, a pair of relatively rotatable winding drums, driving connections between said motor and one of said drums for effecting drum rotation 75 at either a relatively high or a relatively low speed including a fast speed drive control means and a slow speed drive control means, means for effecting operation of one of said drive control means when the other is released including a common manual control element, and separate driving connections between said motor and said other drum.

80 15. In a hoisting mechanism, a motor, a pair of relatively rotatable winding drums, a shaft on which said drums are journaled, driving connections between said motor and said shaft, three pinions fixed to said shaft, two of the same size and the third of a smaller size, driving connections between said small pinion and one of said drums for effecting drum rotation at a relatively low speed, driving connections between one of said larger pinions and said drum for effecting rotation thereof at a relatively high speed, 85 and driving connections between said other large pinion and said other drum.

90 16. In a hoisting mechanism, a motor, a pair of relatively rotatable winding drums, plural speed planetary driving connections between said motor and one of said drums, and a separate planetary driving connection for said other drum.

95 17. In a hoisting mechanism, a motor, a pair of relatively rotatable winding drums, plural speed frictionally controlled planetary driving connections between said motor and one of said drums, and a separate frictionally controlled planetary driving connection for said other drum.

100 In testimony whereof I affix my signature.
ROBERT C. OSGOOD.
